UNITED STATES PATENT OFFICE.

THOMAS EGAN, OF MUSCATINE, IOWA, ASSIGNOR OF ONE-HALF TO J. G. DERMEDY, OF MUSCATINE, IOWA.

TROLLEY-HARP.

SPECIFICATION forming part of Letters Patent No. 773,280, dated October 25, 1904.

Application filed April 14, 1904. Serial No. 203,177. (No model.)

To all whom it may concern:

Be it known that I, THOMAS EGAN, a citizen of the United States, residing at Muscatine, in the county of Muscatine and State of Iowa, 5 have invented a new and useful Trolley-Harp, of which the following is a specification.

This invention relates to overhead trolleys, and one of the primary objects thereof is to provide means for maintaining the trolley in 10 constant contact with the trolley-wire and eliminate the "arc" common in the use of the ordinary type of trolley.

A further object of the invention is to provide a novel means for accomplishing the desired result, which may be attached to the ordinary form of trolley-harp.

A further object of the invention is to provide a connection between the trolley harp and pole, whereby a limited swing of the 20 harp will be permitted to compensate for the swaying of the car owing to uneven road-beds and in rounding curves.

Further objects and advantages of this invention will appear as the nature of the invention is better understood, it being obvious 25 that changes as to form and minor details of construction may be made without departing from or sacrificing any of the essential elements of this invention.

30 In the drawings, Figure 1 is a front view of the trolley constructed in accordance with my invention, and Fig. 2 is a side view of the same.

In carrying out the invention the usual trolley-harp 1 may be used, having in one end thereof a recess 2. The pole 3 is bifurcated, as at 4, and between the bifurcated arms 4^a is pivoted an interposed connecting member 5, which is seated in the recess 2 and held rigidly 35 therein by a transverse pin 6. The lower end 7 of the connecting member is substantially angular, so that a line drawn in the path of the arc scribed by said end in swinging would intersect the curved or concave end 40 of the pole which is between the arms 4^a and which is scribed on a different arc. The oppositely-located shoulders 5^a on the coupling member 5 will also contact with the ends 45 of the arms 4^a to further insure the limit of

swing of the trolley-harp. This arrangement will permit the harp to swing from side to side, so that the trolley-wheel will at all times track with the conductor-wire irrespective of the vibration of the car to which the pole is attached. 50

It is also the purpose of this invention to provide a finder for the trolley-wheel, and this finder consists of two arcuate spring-arms 9 and 10, having attaching-terminals 11 and 12, which are inwardly bent at substantially 55 right angles to the planes of the arms, so as to lie snugly against the opposite faces of the trolley-harp. The terminals are also provided with alining openings, which coincide with similar openings in the trolley-head, so 60 that bolts 14 may be inserted through the said openings and riveted or otherwise fastened, so as to hold the parts in place. It will be observed that the outer edges of the 65 spring-arms are slightly beveled or inclined, 70 as at 15, so as to facilitate the introduction of the conductor therebetween and into contact with the trolley-wheel. Inasmuch as the intermediate portions of the arms are close together and directly on either side of the longitudinal center of the wheel and the portions on either end diverge or curve outward, the conductor or feed-wire will readily be guided 75 into contact with the wheel. In practice it is contemplated to have the intermediate portions of the arm so close together that they will have to slightly spring apart to permit the wire to contact with the wheel; but when the wheel and wire properly coat the wheel 80 cannot easily jump the trolley. 85

I claim—

1. Means for maintaining constant contact between a trolley and a wire which consists of two arcuate spring-arms adjacent to each other on the same plane, and provided with 90 right-angularly disposed terminals engaging opposite sides of the trolley-harp, the opposite ends of the arms being free and outwardly disposed.

2. A guard for trolleys comprising a pair of 95 mutually-cooperating guard members which are bowed toward one another with their free extremities flared longitudinally and also

transversely outward, the other ends of the members being provided with laterally-directed attaching-brackets.

3. The combination with a trolley-harp and 5 a grooved trolley-wheel carried thereby, of guard members secured to opposite sides of the harp in front of the axis of the wheel and bowed inwardly and rearwardly toward each other across the upper peripheral edge 10 portion of the trolley-wheel and disposed

substantially tangential with respect thereto with their inner edges received in the groove of the wheel.

In testimony that I claim the foregoing as my own I have hereto affixed my signature in 15 the presence of two witnesses.

THOMAS EGAN.
